US00D618171S

(12) **United States Design Patent**
Tatehata et al.

(10) **Patent No.:** US D618,171 S
(45) **Date of Patent:** ** Jun. 22, 2010

(54) **RECHARGEABLE BATTERY**

(75) Inventors: **Shouji Tatehata**, Fukushima (JP);
Atsuhiro Kumagai, Tokyo (JP); **Osamu Nagashima**, Tokyo (JP); **Akiko Hikita**, Tokyo (JP)

AU 158108 S 6/2005

(73) Assignee: **Sony Corporation**, Tokyo (JP)

(**) Term: **14 Years**

(21) Appl. No.: **29/311,525**

(22) Filed: **Apr. 13, 2009**

CLAIM

The ornamental design for a rechargeable battery, as shown and described.

DESCRIPTION

FIG. 1 is a perspective view of a rechargeable battery showing our new design;

FIG. 2 is a front elevational view thereof;

FIG. 3 is a top plan view thereof;

FIG. 4 is a bottom plan view thereof; and

FIG. 5 is a cross sectional view along lines 5—5 of FIGS. 2 and 3.

FIG. 6 is a perspective view of another embodiment of a rechargeable battery showing our new design;

FIG. 7 is a front elevational view thereof;

FIG. 8 is a top plan view thereof;

FIG. 9 is a bottom plan view thereof; and,

FIG. 10 is a cross sectional view along lines 10—10 of FIGS. 7 and 8.

Portions in broken lines are for illustrative purposes only and form no part of claimed design.

1 Claim, 10 Drawing Sheets

Related U.S. Application Data

(63) continuation of application No. 29/300,683, filed on Apr. 25, 2008, now Pat. No. Des. 590,769, and a continuation of application No. 29/300,682, filed on Apr. 25, 2008, now Pat. No. Des. 590,341, and a continuation of application No. 29/300,681, filed on Apr. 25, 2008, now Pat. No. Des. 590,335, and a continuation of application No. 29/300,680, filed on Apr. 25, 2008, now Pat. No. Des. 592,130, and a continuation of application No. 29/300,679, filed on Apr. 25, 2008, now Pat. No. Des. 590,334, and a continuation of application No. 29/300,690, filed on Apr. 25, 2008, now Pat. No. Des. 590,337.
